US00D781310S

(12) **United States Design Patent** (10) **Patent No.:** **US D781,310 S**
Mariet et al. (45) **Date of Patent:** **** Mar. 14, 2017**

(54) **DISPLAY SCREEN OR PORTION THEREOF WITH GRAPHICAL USER INTERFACE**

(71) Applicant: **Google Inc.**, Mountain View, CA (US)

(72) Inventors: **Robertus Christianus Elisabeth Mariet**, Sunnyvale, CA (US); **Manuel Christian Clement**, Felton, CA (US)

(73) Assignee: **Google Inc.**, Mountain View, CA (US)

(**) Term: **15 Years**

(21) Appl. No.: **29/567,766**

(22) Filed: **Jun. 13, 2016**

Related U.S. Application Data

(62) Division of application No. 29/543,498, filed on Oct. 26, 2015, now Pat. No. Des. 761,837, which is a division of application No. 29/438,614, filed on Nov. 30, 2012, now Pat. No. Des. 745,020.

(57) **CLAIM**

The ornamental design for a display screen or portion thereof with graphical user interface, as shown and described.

DESCRIPTION

The FIGURE is a front view of an image of a display screen or portion thereof with graphical user interface according to our design.

The broken line showings of portions of a display screen, text, and other features in the figure are environmental only and form no part of the claimed design.

1 Claim, 1 Drawing Sheet
